UNITED STATES PATENT OFFICE.

JAMES RUSSELL, OF ST. LOUIS, MISSOURI.

IMPROVEMENT IN APPARATUS FOR DRAWING ON BOOTS.

Specification forming part of Letters Patent No. 129,175, dated July 16, 1872.

Specification describing a certain Apparatus for Drawing on Boots, invented by JAMES RUSSELL, of the city and county of St. Louis and State of Missouri.

My improvement consists essentially of a strap having at each end a hook to engage the boot-tugs, and of suitable length to pass around behind the person.

Figure 1 is a perspective view of my improvement. Fig. 2 shows the manner of using the same.

A is a strap that may be made of any suitable material having but little elasticity; (I have used the woven material used for boot-tugs.) At each end of the strap is a hook, B, to engage the boot-tugs. The form of the hook may be varied to suit the fancy or convenience. The strap at one end is passed through the hook and attached to a slip-buckle, C, which

may be slipped on the strap to increase or diminish the length of the same to suit the size of the user.

When using the boot-drawer the strap is passed behind the buttocks and the hooks B engaged in the tugs D of the boot; then, by straightening the leg, the boot is drawn on with great ease, without any strain upon the spine, as is the case when boots are drawn on by hand; but, if desired, the operation may be assisted by the hands.

I claim as my invention—

The boot-drawer, consisting of the extensible strap A C and hooks B, as and for the purpose set forth.

JAMES RUSSELL.
